MOUNTING

Irving P. Whitehouse, Erie, Pa., assignor to Hugh C. Lord, Erie, Pa.

Original No. 1,905,540, dated April 25, 1933,
Serial No. 350,346, March 27, 1929. Application
for reissue September 9, 1933. Serial No.
688,863

26 Claims. (Cl. 248—14.2)

This invention is particularly designed to absorb vibration. In many environments it is desirable to so form the mounting that it will resist extended movement much beyond a small 5 vibration range. Such a mounting is shown in application, Serial Number 220,156, filed by Hugh C. Lord, Sept. 17th, 1927. With the present invention a construction is shown in which this 10 action may be more abruptly controlled than in the illustration of said application. Features and details of the invention will appear from the specification and claims.

A preferred embodiment of the invention is illustrated in the accompanying drawing as follows:—

Fig. 1 shows a sectional view of the mounting in place, as shown, being in place as an engine mounting for an automobile.

Fig. 2 a central section of the mounting detached and free from load.

Fig. 3 an end view of the mounting.

1 marks the central member of the mounting which is in the form of a hollow pin, 2 a rubber wall surrounding the central member, and 3 the 25 outer shell. The rubber wall is preferably bonded during vulcanization to the central member and to the outer shell and where this vulcanization is accomplished by heat the cooling of the rubber puts this rubber under initial tension so that 30 while it is very sensitive to vibration it is quite resistant to any extended movement. The central pin has an opening 4 through it by means of which it may be readily secured.

The shell of the mounting is ordinarily secured 35 by a press fit in a socket 5a, the socket being in one of the supporting arms 5 of an automobile engine. The socket terminates near the upper surface of the arm forming a shoulder 6 against which the shell 3 seats.

40 A bracket 7 is secured to an automobile channel frame 8 by rivets 8a and forms a base 7a on which the rubber seats. A securing bolt 9 extends through the opening 4 and through a plate 10 which extends over the top of the rubber, the 45 bolt 9 being supplied with a nut 9a by means of which the plate is clamped on the upper end of the central member.

The rubber projects beyond the outer shell as 50 at 11 and also bulges at 12 from the edge toward the center member giving to the end a convex

tapered formation. The rubber projects at 13 from the shell 3, the projection being sufficient to extend through the shoulder 6 and still project to some extent above the top surface of the arm 5 and seats against the underside of the plate 10. 55 The upper surface 14 of the rubber is depressed toward the center member giving to the upper surface a concave tapered formation and this depression is more pronounced than the bulge 12. The marginal lines indicating the taper of the 60 surfaces 12 and 14 are not quite parallel, the lines representing this being closer together at the center than at the outer edge (see Fig. 2).

In other words, the rubber at the outer edge is 65 somewhat thicker than at the center. With the 65 bulging end 15 on the bottom, as shown in Figs. 1 and 2, and the weight placed upon the shell 3, the weight of the motor, or other vibrating instrument depresses the shell 3 to a point that brings the surface 12 just into contact with the 70 surface 7. At the same time this movement of the shell tends to straighten the upper surface of the rubber. If the two surfaces 12 and 14 are parallel and the weight is adjusted to just the load-carrying capacity of the rubber between 75 the shell and pin the two surfaces 12 and 14 would contact the plates 7 and 10 without pressure. The rubber at the edges is entirely in neutral and does not begin to add its resistance to the resistance of the rubber spanning the 80 space between the shell and pin in some instances with sufficient abruptness. It is desirable, therefore, to make the rubber slightly 85 longer at the outer edge than at the center and so adjust it that there is a slight initial compression at the outer edge of the upper surface 14 and just contacts on the lower surface 12. As a result with the center pin mounted on a lower seat and the plate 10 drawn down against the upper surface 14 the outer shell and with it the 90 outer edge of the surface 12 will move downwardly subject to this depressing effect of the plate 10 and the normal load. Thus at least the outer edges of the upper surface 14 are under very slight initial compression and the outer 95 edges of the surface 12 are preferably in contact with the seat 7 and under very slight initial compression. By this means the rubber is compressed at the edges of the surfaces 12 and 14 so as to eliminate some of the initial practically 100

- non-resistant quality of the rubber under initial compression, so that with any further movement the resistance may go up very abruptly. Under these conditions, all the rubber is sensitive to 5 incipient vibrations which are peculiar to vibrating members, such as motors, but the rubber is just on the edge of a very abrupt building up of resistance due to the fact of the greater thickness at the edge. It will be understood that 10 under some conditions the upward pressure at the edge of the surface 14 may be greater than the downward pressure of the edge of the surface 12 on the seat 7. This may be accomplished by increasing the bevel of the surface 14 from 15 that of the bevel 12 and with relation to the normal load. It will be noted, therefore, that the downward pressure of the plate 10 on the outer edge of the surface 14 is an added part of the load on the mounting as a whole.
- 20 What I claim as new is:—
1. In a mounting, the combination of a supported and a supporting member having opposing spaced walls; and a dampening member comprising an uncompressed rubber portion arranged between the walls and normally carrying a major portion of the load of the supported member on the supporting member through shear of the rubber and a rubber portion having initial engagement with one of the members and subjected to compression through said engagement and incident to shock on the supported member.
  2. In a mounting, the combination of a supported and a supporting member having spaced walls; and a dampening member comprising a rubber portion under initial tension between the walls and normally carrying a major portion of the load of the supported member on the supporting member through shear of the rubber and a rubber portion having initial engagement with one of the members and subjected to compression through said engagement and incident to shock on the supported member.
  3. In a mounting, the combination of a supported and a supporting member having spaced walls; and a dampening member comprising an uncompressed rubber portion between the walls and normally carrying a major portion of the load of the supported member on the supporting member through shear of the rubber and rubber portions having initial engagement with one of the members subjected to compression through said engagement with a movement of the supported member in both load and rebound directions through shock on the supported member.
  4. In a mounting, the combination of a supported member and a supporting member, one of said members being within the other and said members having spaced walls; and a dampening member comprising an uncompressed rubber portion between the walls and normally carrying a major portion of the load of the supported member on the supporting member through shear of the rubber and a rubber portion having initial engagement with one of the members subjected to compression initially through said engagement and to further compression through shock on the supported member.
  5. In a mounting, the combination of a supported member and a supporting member, one of said members being within the other and said members having spaced walls; and a dampening member comprising a rubber portion under initial tension between the walls and normally carrying a major portion of the load of the supported member on the supporting member
- through shear of the rubber and a rubber portion having initial engagement with one of the members subjected to compression initially through said engagement and to further compression through shock on the supported member. 80
6. In a mounting, the combination of a supported and a supporting member, one of said members being within the other and having spaced walls; and a dampening device comprising an uncompressed rubber portion arranged between the walls normally carrying a major portion of the load through shear of the rubber and a concave rubber projection from said rubber portion, said rubber portion yielding under normal load to bring the concave surfaces into compression engagement with one of the members. 85
7. In a mounting, the combination of a supported and a supporting member, one of said members being within the other and having spaced walls; and a dampening device comprising an uncompressed rubber portion arranged between the walls normally carrying a major portion of the load through shear of the rubber, and a convex rubber projection from said rubber portion, said rubber portion yielding under normal load to bring the convex surfaces into compression engagement with the one member, and said rubber portion having at its opposite end a rubber projection having a depression, the surface of which is adapted to engage one of the members and resist shock between the members through compression. 90
8. In a mounting, the combination of a supported and a supporting member, one of said members being within the other and having spaced walls; and a dampening device comprising an uncompressed rubber portion arranged between the walls normally carrying a major portion of the load through shear of the rubber, and a convex rubber projection from said rubber portion, said rubber portion yielding under normal load to bring the convex surfaces into compression engagement with one of the members, and said rubber portion having at its opposite end a rubber projection having a depression, the surface of which is adapted to engage one of the members and resist shock between the members through compression. 100
- 105
9. In a mounting, the combination of two members, one of the two members including a supporting wall and a rubber element in union with and projecting from the wall into free space and in shear relation to the wall between the members; and means initially compressibly engaging the rubber element restraining through such engagement the shear action of at least a portion of the rubber. 110
- 115
10. In a mounting, the combination of two members, one of the two members including a supporting wall and a rubber element in union with and projecting from the wall into free space and in shear relation to the wall between the members; means loading the element in shear and adapted to engage the rubber element and 120 through such engagement to restrain the shear action of at least a portion of the rubber; and devices pre-loading the element to modify the shear action. 130
11. In a mounting, the combination of two members, one of the two members including a supporting wall and a rubber element in union with and projecting from the wall into free space and in shear relation to the wall between the members; means loading the element in shear 135
- 140
- 145
- 150

- and adapted to engage the rubber element and through such engagement to restrain the shear action of at least a portion of the rubber; and resiliently controlled devices for preloading the 5 element. 83
12. In a mounting, the combination of two members, one of the members including a supporting wall; a rubber element having union with and projecting in shear relation to the wall 10 into free space between the members, one face of the rubber element being inclined to the direction of shear; and means initially compressibly engaging the rubber element restraining through such engagement the shear action of at 15 least a portion of the rubber. 85
13. In a mounting, the combination of two members, one of the members including a supporting wall; a rubber element having union with and projecting in shear relation to the wall 20 into free space between the members, one face of the rubber element being inclined to the direction of shear; means adapted to engage the rubber element to restrain through such engagement the shear action of at least a portion of the rubber; and devices 25 pre-loading the element to modify the shear action. 90
14. In a mounting, the combination of opposing wall portions; a member comprising rubber having union with and projecting from said wall 30 portions into free space and in shear relation thereto, the rubber of one face of the member being convex; and means initially compressibly engaging the convex surface of the rubber restraining through such engagement the shear 35 action of at least a portion of the rubber. 95
15. In a mounting, the combination of opposing wall portions; a member comprising rubber having union with and projecting from said wall 40 portions into free space and in shear relation thereto, the rubber of one face of the member being convex; means adapted to engage the convex surface of the rubber and restrain through such engagement the shear action of at least a portion of the rubber; and devices pre-loading 45 the member to modify the shear action. 100
16. In a mounting, the combination of an outer member having opposing wall portions undeformable under normal load; and a second member comprising a rubber element having union 50 with and projecting from said wall portions, the rubber of said second member being convex at one end and concave at the opposite end. 105
17. In a mounting, the combination of an outer member having opposing wall portions undeformable under normal load; and a second member comprising a rubber element having union with and projecting from said wall portions, the rubber of said second member being convex at one end and concave at the opposite end and the rubber of the second member being thicker 55 adjacent to the opposing walls than toward the center of the member. 110
18. In a mounting, the combination of an outer member having opposing wall portions undeformable under normal load; a second member comprising a rubber element having union with and projecting from said wall portions, the rubber of said second member being convex at one end and concave at the opposite end; and means 60 initially compressibly engaging the convex end of the member and restraining through such engagement the shear action of at least a portion of the rubber. 115
19. In a mounting, the combination of an outer member having opposing wall portions unde- 65
- formable under normal load; a second member comprising a rubber element having union with and projecting from said wall portions, the rubber of said second member being convex at one end and concave at the opposite end; means 70 initially compressibly engaging the convex end of the member and restraining through such engagement the shear action of at least a portion of the rubber. 120
20. In a mounting, the combination of an outer member having opposing wall portions undeformable under normal load; a second member comprising a rubber element having union with and projecting in shear relation into free space 75 between said wall portions, the rubber at one end being convex and the mounting at the opposite end being concave; means adapted to engage the convex surface of the rubber and to restrain through such engagement the shear action of at least a portion of the rubber; and devices pre-loading the element, the pre-loading pressure on the convex end being countered on the outer portions of the concave end of the mounting. 125
21. In a mounting, the combination of a member having opposing outer wall portions undeformable under normal load; a second member comprising rubber portions having union with and projecting in shear relation into free space 80 between said wall portions, the rubber at one end being convex and the mounting at the opposite end being concave; means adapted to engage the convex surface of the rubber and to restrain through such engagement the shear action of at least a portion of the rubber; and devices 85 pre-loading the element to modify the shear action. 130
22. In a mounting, the combination of a supported and a supporting member having opposingly spaced wall portions; and a dampening member comprising rubber portions between the walls carrying a major portion of the load of the supported member on the supporting member 90 through shear of the rubber, and a rubber portion having initial engagement with one of the members restraining the shear action of at least a portion of the rubber. 135
23. In a mounting, the combination of a supported and a supporting member having opposingly spaced walls; a dampening member comprising a rubber portion between the wall portions carrying a major portion of the load of the supported member on the supporting member 95 through shear of the rubber, and an inclined rubber portion adapted to engage with one of the members and to restrain through such engagement the shear action of at least a portion of the rubber; and devices pre-loading the mounting to force the engagement of the inclined rubber portion to modify the shear action. 140
24. In a mounting, the combination of two members, one of the two members including a supporting wall and a rubber element in union 100 with and projecting from the wall into free space and in shear relation to the wall between the members, one end of the rubber being inclined toward the wall, said rubber element yielding under load to bring the inclined surface into compression engagement with one of the members. 145
25. In a mounting, the combination of two members, one of the two members including a supporting wall and a rubber element in union 105 with and projecting from the wall into free 150

space and in shear relation to the wall between the members, one end of the rubber being inclined away from the wall and the other end of the rubber being inclined toward the wall; and 5 means compressibly engaging the ends of the rubber element restraining through such engagement the shear action of at least a portion of the rubber.

26. In a mounting, the combination of oppos-

ing wall portions; a member comprising rubber having union with and projecting from said wall portions into free space and in shear relation thereto, the rubber of one face of the member being concave; and means compressibly engaging the concave surface of the rubber restraining through such engagement the shear action of at least a portion of the rubber.
